J. K. PUMPELLY.
BATTERY GRID.
APPLICATION FILED JUNE 8, 1908.

927,812.

Patented July 13, 1909.

UNITED STATES PATENT OFFICE.

JAMES K. PUMPELLY, OF INDIANAPOLIS, INDIANA, ASSIGNOR OF ONE-HALF TO EDGAR M. VAN NORSTRAN, OF INDIANAPOLIS, INDIANA.

BATTERY-GRID.

No. 927,812.

Specification of Letters Patent.

Patented July 18, 1909.

Application filed June 8, 1908. Serial No. 437,268.

To all whom it may concern:

Be it known that I, JAMES K. PUMPELLY, a citizen of the United States, residing at Indianapolis, in the county of Marion and 5 State of Indiana, have invented certain new and useful Improvements in Battery-Grids, of which the following is a specification.

My invention relates to improvements in battery grids.

One of the objects of my invention is to provide a plate or grid adapted to present a large superficial surface to the contacting excitant relative to its weight.

Another object of my invention is to provide in a two part grid a proportionally large quantity of active material and an extensive surface contact between the metal supporting portion of the grid and the pasty contents, as a means for providing low internal resistance and large current capacity. 10 And yet another object of my invention is to provide a two part grid which is cheap of construction, capable of being cast from a simple mold and easily and quickly pasted and secured together to constitute substantially a single piece grid structure.

Other and further objects of my invention will become apparent to those persons who are skilled in the art, from a consideration 15 of the specification, taken in conjunction with the drawing, wherein;

Figure 1 is a side elevation of my two plate grid; Fig. 2 is a similar reverse view of the same; Fig. 3 is a cross section taken 20 on line 3—3 of Fig. 1; Fig. 4 is a transverse cross section, taken on line 4—4 of Fig. 1.

In all of the views the same reference characters indicate the same parts.

The grid is composed of two plates 10 and 25 11, similar in every respect with the single exception that plate 10 is provided with laterally extending spurs 12, 12. Plate 11 having registering perforations 13. Each plate is provided with laterally extending, 30 tapering, strengthening ribs 14—14—inclosed between the two plates when the element has been completed. It will be noticed that 35 these ribs are located alternately with respect to the ribs of the opposite plate, thus dividing the active material into thin long sections and breaking up the active material, so to speak, so that the distance from any 40 part thereof to the supporting metallic conductor of the grid is very short. The 45 closed active material being so hedged about

by the metallic housing as to render it practically impossible for it to fall away or otherwise be severed from the structure.

Inwardly projecting edges, or frames, 15, 15, surround the perforated sheets 16—16 and are brought into contact and at their adjoining contacts 17 the parts may be 50 burned together to thus unite the plates 10 and 11 into a single element in lieu of the spurs 12 and perforations 13, or if desired, 55 both methods of permanently uniting the plates may be employed.

Conducting and strengthening ribs 18—18 extend vertically and are preferably thinner than the ribs 14 although they may be made 60 tapered and placed in the same relation with regard to their respective alternate positions, if desired.

Active material 19 is shown in Figs. 3 and 4, and it will be noted that there is a very 65 large superficial contact between said active material and the conducting structure.

A lug such as 20, 20 extends vertically from each plate to form electric terminals for the composite plate. They may be 70 burned together if desired, or they may be 75 separately burned to or otherwise connected to the conducting strip of the battery of which the grid forms one element. The plates are preferably cast in molds, of a 80 proper alloy, and each plate is "pasted", or 85 filled with active material, such as an oxid of lead or other active agent, on the ribbed sides, until the interior of the plates are practically filled. Then the plates are 90 placed side by side, so that the spurs 12 register with the perforations 13, and then the plates are pressed tightly together between flat surfaces until the marginal edges 15, 15 are in firm contact the one with the other. 95 The spurs 12 are then turned down, as shown in Fig. 3, to hold the plates together, or the parts may be burned together at the joining contact 17, or both or either means of uniting may be employed.

When the tapered ribs 14 enter the active material of the opposite plate it displaces the active material by its wedge-like action, and tends to compact the active material on either side thereof, thereby increasing its 105 density so as to condense a relatively large quantity within a comparatively small space. The act of compacting the active material resulting from the means employed to unite the plates affords a cheap mode of construc- 110

tion, brought into effect without the necessity of an extra operation to produce this highly desirable quality of the element.

The plate proper is so reinforced with 5 ribs, and the material of which the plate is preferably composed, an alloy of lead and antimony, is of such a resilient nature that the enlargement, due to the swelling of the active material under charge and discharge, 10 is very largely prevented, and when it does occur the metallic parts follow the active material as it contracts and thus active contact is always preserved.

While I have shown and described a single 15 embodiment of my invention for purposes of illustration it is evident that considerable departure may be made therefrom without departing from the spirit and scope of the claims.

20 Having thus described my invention, what I claim is;

1. A two-part battery grid comprising

two perforated plates having inwardly projecting tapered ribs extending beyond the marginal ribs, and marginal ribs adapted to 25 be brought into contact to close the housing and spurs on one plate adapted to enter perforations in the other plate to hold the plates together.

2. A two-part battery grid comprising 30 two perforated plates, internally projecting marginal ribs adapted to be brought into contact the one with the other, a series of internal strengthening ribs extending longitudinally of the plates and adapted to enter 35 the opposite plate and another series of ribs extending vertically of the plates and means for holding the plates together.

In testimony whereof I hereunto set my hand in the presence of two witnesses.

JAMES K. PUMPELLY.

In the presence of—

ELLA GOSSETT,

MARY GRAY.
